UNITED STATES PATENT OFFICE.

JAMES S. THOMPSON, OF PELHAM, NEW YORK, ASSIGNOR TO THE AMERICAN BRAKE SHOE & FOUNDRY COMPANY, OF WILMINGTON, DELAWARE, A CORPORATION OF DELAWARE.

BRAKE-SHOE.

1,373,538.

Specification of Letters Patent.

Patented Apr. 5, 1921.

Application filed December 17, 1919. Serial No. 345,530.

To all whom it may concern:

Be it known that I, JAMES S. THOMPSON, a citizen of the United States, residing at Pelham, in the county of Westchester and State of New York, have invented certain new and useful Improvements in Brake-Shoes, of which the following is a specification.

This invention relates primarily to locomotive brake shoes of that type which are commercially known as center-fastening shoes and are provided with a single fastening lug located at or about the center of the shoe to engage an opening provided for it in the brake head.

The invention has for its objects to reduce to a minimum the wear on the brake head by the lug of the shoe, and to construct the lug and associate it with the reinforcing back of the shoe in a novel manner to avoid damage to the brake head and to the shoe by reason of the strains and blows to which the lug is subjected in actual service.

More particularly my invention has for its object to provide a strong and substantial lug for a center-fastening shoe which presents smooth, non-wearing surfaces to the brake head and which is so engaged and supported by the reinforcing back of the shoe that the forces or blows which are applied to the lug in the application of the brakes in service will be distributed through the reinforcing back over a considerable area of the shoe to thereby avoid the danger of fracturing the body of the shoe beneath the lug which might happen if the forces or blows were transmitted by the lug entirely to that portion of the body of the shoe beneath the lug.

The objects of my invention will more fully appear in the detail description thereof as embodied in a selected form in the accompanying drawings, referring to which—

Figure 1 is a perspective view showing my invention embodied with one form of reinforcing back.

Fig. 2 is a fragmentary perspective view of that part of the back with which the lug is directly engaged.

Fig. 3 is a perspective view of the lug detached from the back.

Fig. 4 is a transverse sectional view through the lug of a shoe embodying the invention.

Fig. 5 is a fragmentary perspective view illustrating a modification of the invention. Referring to the drawings, the reinforcing back 6 is provided with an opening 7 formed by cutting the back on parallel lines extending longitudinally thereof and on a transverse line connecting said parallel cuts and striking up the supports 8, 8. The lugs 9 may be formed out of a strip of strap metal which is bent to form an arch with oppositely disposed outstanding feet 10, 10. The upper part of the lug is preferably wider than the lower part whereby a shoulder 11 is formed on each side of each leg of the lug at the juncture of the upper wide and the lower narrow parts of the lug. I prefer that each shoulder be perpendicular to the edge of the lug. The narrow part of the lug may be formed by cutting away the edges from each shoulder to the end of the feet.

The lug may be assembled with the reinforcing back by pushing it up through the opening 7 and then forcing the supports 8 into engagement with the shoulders 11, or if the feet of the lug are not bent outwardly, they can be pushed down through the opening 7 from the top of the back until the shoulders engage the supports, after which the feet may be bent outwardly into position to engage the back. The body 12 is cast on the back and lug in the usual manner and in any form desired and the body metal is preferably run up into the lug to or about the level of the upper edges of the supports 8 to form a reinforcing and strengthening filler 13 for the lug and a bearing for the key.

My improved lug is designed and proportioned to fill the opening provided for it in the brake head so that there will be a fair but not a tight fit between the lug and the head. For practical reasons, which are well understood, it is not possible to fit the brake shoe to the head so closely and so snugly that movement of the shoe relative to the head will be prevented. In all shoes which are secured to brake heads through the medium of a single lug there is always possible a lengthwise movement of the lug in the head, to a more or less extent, when the brakes are applied as well as when the shoes are hanging free. If the lug is made of ductile metal and no provision is made

against such movement the edges of the lug will engage the walls of the opening in the head with a cutting wear, due to the movement of the shoe relative to the head, which 5 will in course of time seriously damage the brake head. My invention avoids the possibility of this damage to the brake head by protecting the lug so that its edges will not destructively engage the brake head with a 10 cutting wear. The lug is provided with flat bearing surfaces by the supports 8 of sufficient area to engage the opposite walls of the opening in the head without wearing the head destructively. The supports 8 are 15 preferably flush or substantially flush with the edges of the upper wide part of the lug, and since these supports form broad flat non-wearing bearing surfaces which engage the walls of the opening in the head, the 20 edges of the lug above these supports cannot cut into the walls of the opening in the head.

In the ordinary application of the brakes the lug is subjected to pounding or hammering blows of considerable force on its 25 top. If the force of these blows is transmitted directly to a restricted section of the body of the shoe, at or about its center, they may fracture the body and seriously 30 damage the shoe. My invention avoids this by the engagement of the supports 8 with the shoulders 11 on the lug so that blows on the top of the lug will be transmitted primarily direct to the supports and through 35 them to the back. Thus the force of the blow is distributed in greater or less degree over the entire area of the back of the shoe instead of being concentrated over a small section at or about the center of the 40 shoe. It is my opinion, based upon an extensive practical experience in the brake shoe art, that this distribution of the force of the blow imparted to the lug when the brakes are applied will entirely avoid the 45 likelihood of fracture to the shoe from such blow.

Thus my invention, in its preferred form, will protect the brake head from cutting wear by the lug and will protect the shoe 50 from destructive effect of the blows upon the lug in the application of the brakes.

In the modified construction of Fig. 5 the supports 8', 8" do not engage shoulders on the lug but lie snugly against the edges 55 of the lug in frictional engagement therewith. These supports form bearing surfaces for the lug against the walls of the opening in the brake head to protect the brake head against cutting wear from the 60 lug.

The reinforcing back and the lug are made of ductile metal and in any form desired for use on any kind of shoes to which the invention is or may be adapted. The construction is such that it is not necessary to

run the body metal up on the outside of the lug to reinforce and strengthen the lug and to fill the opening in the brake head. The lug itself is of sufficient size to fill the opening in the brake head and it is so constructed and protected that cutting wear by the lug on the brake head is entirely avoided. 70

In the drawings I have shown the invention embodied with one form of back and in a center-fastening locomotive driver shoe, 75 and it is believed that this is sufficient for the purposes of this application. The invention may be embodied with backs and shoes of other forms including, of course, car shoes having centrally disposed fastening 80 lugs, and I reserve the right to make all such adaptations and embodiments, and to make any changes in the form, proportion and construction of parts as fairly fall within the scope of the following claims. 85

I claim:

1. A brake shoe having a reinforcing back and a fastening lug with open ends extending transversely of the back, parts of the back being arranged at the open ends 90 of the lug and extending across said open ends to engage a brake head and reduce the wear on the brake head by preventing the ends of the lug from engaging with the brake head. 95

2. A brake shoe having a reinforcing back and a fastening lug with open ends extending transversely of the back, parts of the back being arranged at the open ends of the lug and extending across said open ends, 100 said parts being positively engaged with the lug to support the lug against the force of blows on the top thereof.

3. A brake shoe having a reinforcing back and a fastening lug with open ends extending transversely of the back, parts of the back being seated in the lug at the open ends thereof and extending across said open ends to form bearings for the lug against a brake head and to support the lug against the force 110 of blows on the top thereof. 105

4. A brake shoe having a reinforcing back provided with an opening therein, a fastening lug for the shoe comprising an arch shape metal strip arranged in said opening 115 transversely of the back, and means integral with the back and located adjacent said lug across the open ends thereof to prevent the edges of the lug from cutting a brake head. 110

5. A brake shoe having a reinforcing 120 back provided with an opening therein, a fastening lug for the shoe comprising an arch shape metal strip arranged in said opening transversely of said back, and projections struck up transversely from the 125 back at the open ends of said lug to engage the brake head and prevent the edges of the lug from cutting said head.

6. A brake shoe having a reinforcing back provided with an opening therein, a fasten- 130

ing lug for the shoe comprising an arch shape metal strip arranged in said opening, and transverse projections on the back engaging and supporting the lug against the 5 force of blows on the top of the lug.

7. A brake shoe having a reinforcing back provided with an opening therein and up-standing supports parallel with the transverse edges of said opening, and a fastening 10 lug for the shoe arranged in said opening and engaged with said supports.

8. A brake shoe having a reinforcing back provided with supports struck up transversely therefrom and forming an opening 15 therebetween, and a fastening lug for the shoe arranged in said opening and engaged with said supports.

9. A brake shoe having a reinforcing back provided with an opening therein and supports adjacent thereto, and a fastening lug 20 for the shoe arranged in said opening and having shoulders engaging the top edge of said supports.

10. A brake shoe having a reinforcing back 25 provided with an opening therein, and a fastening lug for the shoe comprising an arch shape metal strip arranged transversely in said opening and provided with shoulders on its edges, and supports on the back 30 upstanding against the edges of the lug, and abutting said shoulders to prevent said edges from cutting the brake head and to support the lug against the force of blows on top of the lug.

35 11. A brake having a reinforcing back

provided with an opening therein, a fastening lug for the shoe comprising an arch shape metal strip arranged in said opening, supports on the back bridging the open ends of said lug and extending upward part way 40 to the top of the lug, and a body cast on said back and lug with the body metal extending up in the lug substantially flush with the top of said supports.

12. A brake shoe having a reinforcing 45 back and a fastening lug with open ends extending transversely of the back, parts of the back being struck up therefrom and forming bearing surfaces extending entirely across the lug from side to side thereof at 50 the open ends of the lug.

13. A brake shoe having a reinforcing back and a fastening lug with open ends extending transversely of the back, parts of the back being struck up therefrom and 55 seated in the open ends of the lug to support the lug against the force of blows on the top thereof and forming bearing surfaces extending entirely across the lug from side to side thereof at the open ends of the lug. 60

14. A brake shoe having a reinforcing back and a fastening lug with open ends extending transversely of the back, parts of the back being struck up transversely therefrom and seated in the upstanding edges of 65 the lug to support the lug.

JAMES S. THOMPSON.
